UNITED STATES PATENT OFFICE

PRESTON L. ANDREWS, OF BROOKLYN, NEW YORK, ASSIGNOR TO P. L. ANDREWS CORPORATION, OF BROOKLYN, NEW YORK, A CORPORATION OF NEW YORK

CARRIER BAG

Application filed January 6, 1925. Serial No. 787.

- This invention relates to receptacles of sheet material, more particularly to paper envelopes with carrying attachments fastened thereto. It is primarily concerned with paper envelopes having attachments of cardboard fastened to them for the purpose of carrying the envelope. Of course it will be understood that the invention in its broader phases is not limited to such use.
- 10 It is an object of the present invention to provide an ordinary envelope with a pair of carrying attachments, such that when they register with each other the envelope will be locked shut.
- 15 It is a further object to provide one of the carrying attachments with means to guard the edge of the envelope, and to reinforce the handle and the top of the envelope.
- Another object is to provide an envelope 20 with a long flap reinforced by one of the carrying attachments which has a projecting tongue on it to insure positive locking of the envelope.
- The above and various other features and 25 objects of the invention will now be described more in detail with particular reference to the accompanying drawings, in which
- Figure 1 is a plan view of the front of an envelope having its flap open, with an embodiment of the present invention attached thereto;
- Figure 2 is a plan view of the back of the envelope shown in Figure 1;
- Figure 3 is an enlarged sectional view on 35 the line 3-3 of Figure 1, looking in the direction of the arrows;
- Figure 4 is a view similar to Figure 1, except that the flap of the envelope is closed;
- Figure 5 is a plan view of the back of the envelope shown in Figure 4;
- Figure 6 is an enlarged sectional view on 45 the line 6-6 of Figure 4, looking in the direction of the arrows.
- Similar characters of reference designate
- similar parts in each of the accompanying drawings.
- The reference character 1 denotes an envelope or other receptacle of sheet material to which attachments 2 and 5 are secured 50 for the purpose of carrying the same.
- In the process of manufacturing, the attachment 2 is secured, preferably pasted or glued, to the flap 6 of the envelope by its attaching portion 8 which is positioned so 55 that its edge, except for a projecting tongue 19, is flush with the edge 14 of the said flap. The attachment has a patch portion 3 adhesively secured to the front 11 of the envelope. The said patch portion is cut from 60 the handle portion 9 and is integral with the attaching portion 8.
- The second attachment 5 is secured by its attaching portion 7 as shown by the stippled area in Figs. 2 and 5, to the back 12 of the envelope. The attaching portion has a well or unglued portion 20 for receiving the tongue 19. A crease 13 is in the upper edge 65 of the said attaching portion and is positioned to facilitate opening and closing of 70 the flap 6. A handle portion 10 is integral with the attaching portion and has a cut-out portion 15 which will fit a person's hand or fingers.
- The appearance of the upper portion of 75 the envelope in section after having the present invention incorporated in it, may be seen in Figure 3. The envelope as it is ready for use, has its flap 6 open with attachment 2 secured thereto, so that the handle portion 9 of the said attachment extends toward the bottom of the envelope. The other attachment 5 is positioned on the back of the envelope so that the handle portion 10 extends above the edge 17 of the envelope, as is best 80 seen in Figure 5.
- An illustration of the front of the envelope when the handles register or coincide with each other may be seen in Figure 4. It is to be observed that the patch 3 serves not 85 90

only to guard the said edge 17 of the envelope, but also to reinforce the attachment and the top of the envelope. The attachment 5 is so positioned on the back of the envelope 5 that lower edge 18 of the cut-out portion is just below edge 16 of the patch. In this manner the hand of the person carrying the envelope is protected from being cut by the edge 18. Furthermore, as edge 16 is the 10 top of the patch 3 and is not sharp, a person is fully protected against sharp edges in carrying the envelope by its handle.

In the use of the envelope, the material is deposited within it, and then the handle 10 15 is bent back slightly about the crease 13 in order that the flap 6 may be closed. Due to the elasticity of the handle 10, it returns to its normal position and positively locks the envelope after the flap 6 is positioned. The 20 manner in which the handle 10 locks the flap 6 may be seen in Figure 6 which shows the position of the various parts of the closed envelope. The tongue 19 on attachment 2 forms an additional lock by fitting between 25 the envelope and the attaching portion 7, as is best seen in Figure 5. Moreover, as the flap 6 is of considerable length in the preferred form of the embodiment of the invention, and is reinforced by the carrying 30 attachment having a tongue at its end, as explained heretofore; the envelope will be locked shut when the handles register and will remain so even if the envelope is dropped or laid down. The edge 14 of the 35 flap 6 is above the crease 13, so that there is ample clearance between the latter and the former when the flap of the envelope is closed.

It is to be observed that the positioning 40 of the attachment on the exterior of the envelope leaves the useful space within the said envelope undiminished.

It is to be further noted that by the use of the present invention, ordinary envelopes 45 may be employed as the receptacles to which the attachments are fastened. This eliminates the use of special machinery for the manufacture of receptacles of sheet material having carrying attachments incorporated in them. In this manner the cost of 50 production of the said receptacles is reduced to a minimum.

Although I have herein shown and described several forms embodying the invention, it will be readily understood that many changes and modifications may be made therein within the scope of the following 55 claims, without departing from the spirit and scope of the invention, it being my intention 60 to claim the same broadly in whatever form its principles may be employed.

What I claim is:

1. The combination with an envelope of 65 sheet material, of a pair of handles, one secured to the flap, and the other to the back of

the envelope, said handles being arranged to be brought into superposed relation by folding of the flap to close the envelope.

2. The combination with a paper envelope, 70 of an attachment comprising a carrying portion and an attaching portion, said attachment being fastened to the back of the envelope, so that the carrying portion is above the top edge of the bag, another attachment 75 similar to the first, and fastened to the flap of the envelope, so that the carrying portion extends toward the bottom of the envelope and away from the edge of the flap.

3. The combination with a paper envelope, 80 of a pair of carrying attachments, one positioned on the back of the envelope to overlie the flap when closed with its handle portion above the top of the envelope, and the other positioned on the flap with its attaching portion flush with the edge of the flap, and arranged to be inverted into registration with the other handle by folding of the flap, to 85 close the envelope, so that when the two handle portions register with each other the flap is necessarily maintained in position to 90 close the envelope.

4. An envelope having a pair of paper handles fastened thereto, one of said handles having a tongue punched from its body portion to provide the handle grip, said tongue 95 being adhesively connected to the envelope body to form a guard patch.

5. A pair of attachments adapted to be fastened to an envelope of sheet material, one of said attachments comprising an attaching portion adapted to be fastened on the flap of said envelope, a handle portion, and a patch cut from the handle portion and integral with the said attaching portion and fastened to the front of the envelope, thereby reinforcing said attachment and guarding the edge of the envelope, and the second attachment comprising a handle portion, and an attaching portion adapted to be fastened to the back of the envelope.

6. The combination with an envelope of sheet material, of a pair of handles, one of said handles being secured to the flap of said envelope and having a tongue projecting beyond the edge of the said flap, the other of said handles being secured to the back of said envelope and forming a pocket therewith, so that when the handles coincide the said tongue is positioned in the pocket between the back of the envelope and the latter handle, and the envelope is locked shut.

7. The combination with an envelope of sheet material, the said envelope being provided with a long flap, of a carrying attachment secured to said flap and reinforcing the same, the said attachment having a tongue projecting beyond the edge of the flap, and a second attachment secured to the back of the envelope and forming a pocket

therewith to receive said tongue for locking the envelope shut.

8. The combination with an envelope of sheet material, the said envelope being provided with a long flap, of a pair of carrying attachments, one of said attachments being secured to said flap and reinforcing the same, the said attachment having a tongue projecting beyond the edge of the flap, and 10 the second attachment secured to the back of the envelope to receive the said tongue and to hold the flap in a locked condition when the envelope is closed.

13 In testimony whereof I have affixed my signature to this specification.

PRESTON L. ANDREWS.
